UNITED STATES PATENT OFFICE.

JAMES C. WOODSON, OF EAST PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC HEATING UNIT.

Application filed August 20, 1924. Serial No. 733,054.

My invention relates to electric heating apparatus and particularly to means for supporting electric resistor units in electric heating apparatus.

5 The object of my invention is to provide an electric resistor supporting member that is strong in construction, durable in operation and easily installed.

In practicing my invention, I provide a 10 metallic supporting member of substantially channel shape that may be secured in proper operative position relatively to the work to be heated. An electric resistor supporting member composed of any suitable refractory material is constructed in such a manner 15 as to permit the location thereof in said channel member in such a manner that it is movable thereon longitudinally relatively thereto. The resistor supporting member 20 comprises a base member of substantially rectangular section having a plurality of aligned upwardly extending straight portions integral therewith.

I have shown a plurality of opposed sets 25 of such upwardly extending members and located therebetween a plurality of upwardly extending members having a straight portion and an overhanging portion. A helically wound resistor member is located in 30 operative position by threading between the straight upwardly extending members and the overhanging members, and is suitably secured to the base member. The base member is perforated adjacent to one end thereof 35 to permit a bolt or other suitable means to be inserted therein to lock the resistor supporting member to the channel member. A plurality of resistor supporting members are 40 located in the channel which are in end-to-end relation thereby permitting the resistor member to be continuously threaded in operative position longitudinally thereof.

In the single sheet of drawings,

45 Figure 1 is a top plan view of a plurality of resistor supporting members located in operative position in a supporting member of substantially channel form;

Fig. 2 is an end elevational view thereof;

50 Fig. 3 is a bottom plan view of a resistor supporting member;

Fig. 4 is an end elevational view thereof;

Fig. 5 is a top plan view of a resistor supporting member; and

Fig. 6 is a side elevational view thereof.

A channel member 11 having flanges 12 55 is so constructed that the flanges 12 have inwardly extending portions 13 to substantially enclose a plurality of refractory resistor supporting members 14.

The resistor supporting member comprises a base member 15 having upwardly extending substantially straight members 16 that are integral therewith and are arranged in opposed sets in substantially aligned relation. A plurality of upwardly extending members 17 are located between opposed sets of members 16 and comprise substantially straight portions 18 and overhanging portions 19. The base member 15 has a plurality of perforations 21 located adjacent 70 to one end thereof to provide a suitable means for securing the ends 22 of resistor member 23 in proper operative position. A plate 24 of any suitable electrically insulating material serves as its terminal board for 75 resistor 23.

A perforation 25 is provided in base member 15 to locate a bolt 26 utilized for locking the resistor supporting member 14 in operative position relatively to channel member 11.

In assembling the unit, the resistor member 23 is threaded between the straight portions of the upwardly extending member and beneath the overhanging portions 19 85 thereby securely locating said resistor in operative position relatively to resistor supporting members. The ends 22 of the resistor member are secured to the base member by means of bolts 27. Any desired number 90 of resistor supporting members 14 are placed in the channel supporting member 11 and moved longitudinally thereto into proper operative position and secured thereto by bolt 26.

It is obvious that this structure provides a resistor supporting member that is simple to construct, durable in operation and simple in installation.

Various modifications and changes may 100 be made without departing from the spirit and scope of the invention, and I desire therefore that only such limitations shall be placed thereon as are imposed by the prior art or are set forth in the appended claims. 105

I claim as my invention:

1. An electric resistor supporting member comprising a base member, a plurality of aligned substantially straight members integral therewith and extending upwardly therefrom, and a plurality of members having an upwardly extending portion and an overhanging portion.
2. An electric resistor supporting member comprising a base member, a plurality of sets of aligned substantially straight members integral therewith and extending upwardly therefrom, and a member having an upwardly extending portion and an overhanging portion.
3. An electric resistor supporting member comprising a base member, a plurality of opposed sets of aligned substantially straight members integral therewith and extending upwardly therefrom, and a plurality of aligned members located between said sets of straight members, having an upwardly extending portion and an overhanging portion.

In testimony whereof, I have hereunto subscribed my name this 14th day of August, 1924.

JAMES C. WOODSON.
